UNITED STATES PATENT OFFICE

2,288,902

AXIAL FLOW PUMP

Knute Hartman, Aurora, Ind., assignor to The
American Well Works, Aurora, Ill., a corpora-
tion of Illinois

Application December 14, 1939, Serial No. 309,198

6 Claims. (Cl. 103—89)

In axial flow pumps submerged in a liquid there has been a severe problem of maintaining the bearing properly lubricated and protecting it from the fluid being pumped. Shaft seals have proved only partially effective with the result that a great deal of trouble has been encountered by virtue of seepage of the pumped fluid into the bearing. This not only adulterates the lubricant but causes corrosion of the bearing surfaces, thus making extensive repairs necessary.

In axial flow pumps rotation must take place between the shaft housing, which is stationary, and the impeller and there is necessarily a slight clearance between them through which the pumped liquid can flow from the high pressure side of the impeller to the shaft. If the impeller is pumping upwardly or toward the shaft housing, high head pressure is thus transmitted through this clearance to the shaft seal. Although the leakage might be very slow, a small leak will nevertheless cause great injury in a relatively short time since the liquid which does leak through the seal accumulates above it and naturally seeps between the bearing surfaces.

According to the preferred form of the present invention this difficulty is overcome by combining two features, first the provision of an elongated passage between the high side of the impeller and the shaft, and second the provision of liquid expelling means which returns such liquid as passes through this passage to the low pressure side of the impeller, thus preventing the building up of a pressure adjacent the shaft which would cause the liquid to penetrate through the seal.

Additional objects and advantages of the invention will be apparent from the following description and from the drawing, in which:

Fig. 1 is a vertical sectional view taken through the axial flow pump chosen for illustration of the invention.

Fig. 2 is a fragmentary sectional view taken approximately on the line 2—2 of Fig. 1.

Fig. 3 is a fragmentary sectional view taken approximately on the line 3—3 of Fig. 1.

A preferred form of the invention has been chosen for illustration and description, in compliance with section 4888 of the revised statutes, but persons skilled in the art will readily perceive other means for accomplishing the same results, and the claims are therefore to be construed as broadly as possible, consistent with the prior art.

In the illustrated form the pump is positioned at the bottom of a tubular casing 11 and may include an impeller 12 positioned within a pump

casing 13, the lower end of which may desirably be somewhat bell-shaped as seen at 14. The impeller 12 is carried by and keyed to a shaft 16 which in turn may carry a bearing sleeve 17 which is journaled within a stationary bearing sleeve 18. The bearing sleeve 18 may be rigidly positioned in a housing 19 which is supported by webs 21 connecting it with the terminal casing member 13. A protecting pipe 22 surrounding pipe 16 is screwed into the housing 19.

To lubricate the bearings 17 and 18 a drip feed lubricator, not shown, is provided above the surface and is so connected that oil is fed to the outside of shaft 16 and flows down this shaft under the protection of pipe 22. Some of this oil will enter between the bearings 17 and 18 from the top of these bearings, and some of it will flow through passage 23 to an annular passage 24 below bearing 18 where the oil will have access to the lower portions of the bearings 17 and 18. To prevent the oil from flowing past the annular passage 24, suitable shaft seal means is provided. This seal has been illustrated as comprising two seal units 26, each of which may include a supporting ring 27 having a driven fit with the housing 19 and a flexible seal member 28 which may be made of leather or oil-resisting rubber. The seal member 28 may desirably be held in contact with the shaft 16 by a coil spring 29, the parts of the unit 26 being held in assembled relation in the manner shown.

Although seal units such as the units 26 are very satisfactory for most purposes, liquid may seep through them if under a substantial pressure. In the illustrated form of pump the impeller 12 should be rotated in a direction to pump liquid upwardly within the casing 13. Under some conditions there would therefore be a considerable head of pressure on the liquid being pumped. Since rotation necessarily occurs between the impeller 12 and the housing 19, it follows that there must be some clearance space between these members with the result that the liquid being pumped has access to the shaft 16 and the seal units 26. Except for the present invention, therefore, the seal unit 26 would be subjected to the pressure produced by the impeller 12. The pumped liquid would accordingly seep through the seals, dilute the lubricant and corrode the bearing surfaces. Even though the seepage were small, the liquid would eventually get above the bearings 17 and 18 with the result that lubricant could not get down to these bearings.

According to the present invention the flow

of the liquid being pumped to the vicinity of the seal units 26 is greatly restricted by restricting at 31 the clearance space between the impeller 12 and the housing 19. To this end the impeller 12 is provided with an upwardly extending hub 32 which telescopes over a portion of the housing 19. The adjacent surfaces of these two members are cylindrically shaped and disposed concentrically with the shaft 16. The result is that they may be fitted quite closely since the journaling of the shaft 16 substantially eliminates lateral play. Nevertheless, it is not practical to prevent leakage in the clearance space even through the restricted portion 31.

To prevent this leakage from building up a pressure which would cause leaking of the seal units 26, the impeller 12 is provided with a drain passage 33 which communicates through internal space 34 with an outlet 36. The outlet 36 is positioned on the suction side of the impeller 12 and close enough to the impeller so that it is subjected to a strong suction by the impeller. Thus, such liquid being pumped as leaks through the restricted passage 31 will flow through the passage 33 and its extension 34 and be drawn out through the outlet 36. To be sure that the liquid will all be drawn out, a plurality of the passages 33 and outlets 36 may be provided and the parts may be positioned to form a drainage channel 37 between the restricted portion 31 and the seal units 26. All of the passages 33 may conveniently communicate with the drain channel 37.

The outlets 36 are illustrated as formed by notches in the bottom of the impeller 12. It will thus be observed that the walls of the notches form radially extending walls on each side of the notches or outlets 36. Any liquid in the outlets 36 will thus be positively rotated with the impeller and will therefore be subjected to centrifugal force which will aid in expelling the liquid from the outlets 36.

The shaft 16 is preferably provided with a streamlined cap 41 screwed thereon. This cap together with the illustrated shaping of the bottom portion 14 of the casing forms a Venturi passage 42 in which the liquid being pumped is moved at high speed by the impeller 12. As is well known, liquid flowing smoothly through a Venturi passage has a reduced lateral pressure and, accordingly, the suction in the nature of cavitation behind the blades of the impeller 12 is in effect reinforced by the Venturi effect to exert a maximum suction on the outlets 36.

From the foregoing it is seen that a pump is provided which may pump a liquid a considerable height so that a high head pressure is produced without any danger that the liquid being pumped will penetrate the shaft seal and interfere with the lubrication of the bearings. The bearings 17 and 18 may be kept thoroughly lubricated without any danger that water will be forced through the seals 29 by the high pressure developed by the pump.

I claim:

1. An axial flow pump including a housing, a shaft extending through the housing, an impeller mounted on the shaft and adapted to rotate in a direction to force liquid toward the housing and forming a restricted clearance space with the housing, a seal between the housing and the shaft, the impeller having a passage communicating with the clearance space and having an outlet on the suction side of the impeller blade and close thereto, a cap on the shaft beyond the

impeller, and an outside casing surrounding the impeller shaped to form a Venturi passageway, with the outlet approximately at the throat of the Venturi passageway.

2. An axial flow pump including a housing, a shaft extending through the housing, an impeller mounted on the shaft and adapted to rotate in a direction to force liquid toward the housing and forming a restricted clearance space with the housing, a seal between the housing and the shaft, the impeller having a passage communicating with the clearance space and having an outlet on the suction side of the impeller blade and close thereto, a cap on the shaft beyond the impeller, and an outside casing surrounding the impeller shaped to form a Venturi passageway, with the outlet being approximately at the throat of the Venturi passageway and having side walls extending generally radially whereby the rotation of the impeller will exert a centrifugal action on the fluid in the outlet, thus aiding the impeller in drawing the liquid from the passage.

3. An axial flow pump including a housing, a shaft extending through the housing, an impeller mounted on the shaft and adapted to rotate in a direction to force liquid toward the housing and forming a restricted clearance space with the housing, a seal between the housing and the shaft, the impeller having a passage communicating with the clearance space and having an outlet on the suction side of the impeller blade and close thereto, a streamlined flow guide on the suction side of the impeller, and an outside casing surrounding the impeller and extending therebeyond, spaced from and surrounding the flow guide and shaped to cooperate with the flow guide to form a Venturi passageway leading to the impeller, with said outlet approximately at the throat of the Venturi passageway.

4. An axial flow pump including a housing, a shaft extending through the housing, an impeller mounted on the shaft and adapted to rotate in a direction to force liquid toward the housing and forming a restricted clearance space with the housing, a seal between the housing and the shaft, the impeller having a passage communicating with the clearance space and having an outlet on the suction side of the impeller blade and close thereto, a streamlined flow guide on the suction side of the impeller, and an outside casing surrounding the impeller and extending therebeyond, spaced from and surrounding the flow guide and shaped to cooperate with the flow guide to form a Venturi passageway leading to the impeller, said outlet being approximately at the throat of the Venturi passageway and having side walls extending generally radially whereby the rotation of the impeller will exert a centrifugal action on the fluid in the outlet, thus aiding the impeller in drawing the liquid from the passage.

5. An axial flow pump including a housing, a shaft extending through the housing, an impeller mounted on the shaft and adapted to rotate in a direction to force liquid toward the housing and forming a restricted clearance space with the housing, a seal between the housing and the shaft, the impeller having a passage communicating with the clearance space and having an outlet on the suction side of the leading edge of the impeller blade and close thereto, and flaring inlet guide means defining the passage adjacent the impeller blade on the suction side thereof and so shaped as to cause the liquid to be pumped to flow smoothly past the outlet with-

out exerting a force of momentum into the outlet, said outlet opening at a reduced portion of the flaring inlet where the liquid moves at high speed.

6. An axial flow pump including a housing, a shaft extending through the housing, an impeller mounted on the shaft, constructed to pump liquid in an axial direction, and adapted to rotate in a direction to force liquid toward the housing and forming a restricted clearance space with the housing, a seal between the housing and the

shaft, the impeller having a passage communicating with the clearance space and having an outlet on the suction side of the leading edge of the impeller blade and close thereto, and flaring inlet guide means so shaped as to cause the liquid to be pumped to flow smoothly past the outlet without exerting a force of momentum into the outlet, said outlet opening at a reduced portion of the flaring inlet where the liquid moves at high speed.

10 KNUTE HARTMAN.
